UNITED STATES PATENT OFFICE.

EDWIN GARST, OF DAYTON, OHIO, ASSIGNOR TO HIMSELF AND WILBER HEATHMAN, OF SAME PLACE.

VALVE-GEAR.

SPECIFICATION forming part of Letters Patent No. 399,397, dated March 12, 1889.

Application filed June 28, 1888. Serial No. 278,407. (No model.)

To all whom it may concern:

Be it known that I, EDWIN GARST, of Dayton, in the county of Montgomery and State of Ohio, have invented a new and Improved 5 Valve-Gear, of which the following is a full, clear, and exact description.

The invention relates to valve-gears for steam-engines.

The object of the invention is to provide 10 a new and improved valve-gear which is simple and durable in construction and automatic in operation, using steam expansively.

The invention consists of certain parts and details and combinations of the same, as will 15 be fully described hereinafter, and then pointed out in the claims.

Reference is to be had to the accompanying drawings, forming a part of this specification, in which similar letters of reference indicate 20 corresponding parts in all the figures.

Figure 1 is a plan view of the improvement as applied. Fig. 2 is an enlarged transverse section of the improvement on the line xx of Fig. 1. Fig. 3 is an enlarged sectional side elevation of the same on the line yy of Fig. 1. Fig. 4 is an enlarged sectional side elevation of the improvement on the line zz of Fig. 1. Fig. 5 is an enlarged plan view of the inlet-valve and its stem detached. Fig. 6 is a sectional side elevation of the same on the line ww of Fig. 5. Fig. 7 is a plan view of the exhaust-valve and its stem detached. Fig. 8 is a sectional side elevation of the same on the line vv of Fig. 7. Fig. 9 is a perspective view of a cam.

In the steam-cylinder A operates the piston B, connected with the piston-rod C, carrying at its outer end a cross-head, D, mounted to slide in guideways E, and pivotally connected by the pitman F with the crank-arm G' of the main driving-shaft G of the engine. In the end of the cylinder A are formed the two ports a and b , leading to the steam-chests A' and A², connected with each other by a channel, A³, into which leads the steam-inlet pipe A⁴.

Over the ports a and b operate the slide-valves H and H', respectively, provided with the ports a' and b' , formed to register with the ports a and b , leading from the steam-chests A' and A² to the cylinder A. The slide-valves H and H' are connected with the valve-stems H² and H³, respectively, extending toward each other

and operated on by a lever, I, pivotally connected by the rod J with the frame K, mounted to slide longitudinally in the bearings K', located directly under the main driving-shaft G. The inner end of the lever I acts alternately on the ends of the valve-stems H² and H³, so that the slide-valves H and H' are actuated alternately from the said lever I in order to open and close the live-steam ports a and b , leading to the cylinder.

Each of the valve-stems H² and H³ is pivotally connected with a lever, H⁴, fulcrumed on the cylinder A and pivotally connected with a rod, H⁵, mounted to slide in suitable bearings held on the cylinder A. On the outer end of each rod H⁵ is coiled a spring, H⁶, one end of which rests against the said bearing and the other end rests against the adjusting-nut H⁷, fastened on the outer end of the rod H⁵. The spring H⁶ has the tendency to close the slide-valve H or H' whenever the respective valve-stem H² or H³ is disengaged by the lever I.

The longitudinally-sliding frame K carries two rods, K² and K³, held transversely on the said frame K and in a horizontal plane with the main driving-shaft G. On the rods K² and K³ is held to slide transversely a frame, L, formed of two plates, between which are held the friction-rollers L' and L², rotating loosely on the said rods K² and K³, respectively. The friction-wheels L' and L² are operated on by a cam, G², secured to the main driving-shaft G and provided with a spiral ridge, G³, fully shown in perspective view in Fig. 9.

The frame L is secured to a transverse rod, L³, held to slide in suitable bearings in the frame A, and pivotally connected with a link, L⁴, pivoted on the arm N' of a bell-crank lever, N, fulcrumed on a suitable bracket on the main frame of the governor O, located at one side of the main driving-shaft G and operated from the latter. The bell-crank lever N is provided on its other arm, N², with a weight, N³, held adjustably on the said arm N², and the latter is also provided with pins N⁴, projecting into an annular groove formed in the collar O', held to slide vertically on the shaft O², mounted to rotate in suitable bearings on the governor-frame, and carrying on its lower end a bevel gear-wheel, O³, meshing into a bevel gear-wheel, O⁴, secured on one

end of a shaft, O^5 , running parallel with the main driving-shaft G , and mounted to rotate in suitable bearings on the governor-frame. On the shaft O^5 is secured a pulley, O^6 , over which passes an endless belt, O^7 , also passing over the main driving-shaft G , which, by the said belt, imparts movement to the governor O .

The collar O' is connected with the ends of ropes or chains P , passing over the pulleys P' , mounted to rotate in a frame, P^2 , secured to the upper end of the vertical shaft O^2 , and the upper ends of the ropes P are secured to the weights P^3 , held to slide in opposite directions on a rod, P^4 , also secured on the upper end of the vertical shaft O^2 . On each outer end of the rod P^4 is secured a collar, P^5 , to limit the outward movement of the weights P^3 , and the latter are connected with each other by springs P^6 , which serve to draw the weights P^3 inward toward each other after having been moved outward by the centrifugal force of the governor O . The weights P^3 take the place of the usual balls of governors and operate in a similar manner to the same.

From the cylinder A also lead the two exhaust-ports c and d , opening into the exhaust-chambers A^5 and A^6 , from which lead the ports e and f into a pipe, A^7 , connected with the exhaust-pipe A^8 , leading to the outside. The ports c and d , e and f are located opposite each other, and are connected with or disconnected from each other by slide-valves Q and Q' , respectively, having the ports c' and d' , respectively, adapted to register with the ports c and d , respectively. The slide-valves Q and Q' are connected with each other by a valve-stem, Q^2 , pivotally connected with a rod, Q^3 , pivoted on the arm R' of a T -shaped lever, R , fulcrumed at R^2 to a bracket on the main frame of the engine. The pivot R^2 is located in the middle of the guideways E , so that the cross-head travels the same distance on each side of the said pivot. The lever R is also provided with the arms R^3 and R^4 , extending in opposite directions and at right angles to the arm R' , each of the arms R^3 and R^4 being bent upward at the outer ends, R^5 and R^6 , as is plainly shown in Fig. 4, and the said curved ends R^5 and R^6 being alternately engaged by a friction-wheel, D' , held on the cross-head D .

The operation is as follows: When the piston B is in the position shown in Fig. 4, the live steam entering the steam-chest A^2 passes through the ports b' and b into the cylinder A and pushes the piston B forward in the direction of the arrow g' . A rotary motion is thus imparted to the main driving-shaft G in the direction of the arrow h' , so that the cam G^2 acts on the friction-wheel L' and holds the frame K in its extreme outward position, so that the rod J , connected with the lever I , holds the slide-valve H' in the position shown in Fig. 4, whereby the port b' registers with the port b , as above mentioned. When the

cam G^2 has traveled from the point 4 to the point 5, the slide-valve H' remains in this position, and when the cam passes over the wheel L' from the point 5 to the point 6 the lever I swings to the other side, and, the spring H^6 presses on the rod H^5 , the lever H^4 forces the valve-stem H^3 to the left, so that the port b in the cylinder is closed by the slide-valve H' . The piston B is then near the end of its stroke, and the part 1 2 of the cam G^2 now comes in contact with the friction-wheel L^2 and from 2 to 3 moves the valve the lap, so that the frame K is moved forward and the lever I commences to act on the valve-stem H^3 , whereby the slide-valve H is moved in the direction of the arrow g' and the port a' opens into the port a , when the cam G^2 travels from the point 3 to the point 4, at which latter point the ports are fully opened. The live steam now enters through the steam-chest A' into the inner end of the cylinder and forces the piston B in the reverse direction of the arrow g' . When the piston B is in the position shown in Fig. 4, the slide-valve Q disconnects the ports d and f , while the slide-valve Q connects by its port c' with the cylinder-port c and the exhaust-port e . When the piston travels in the direction of the arrow g' , the exhaust-steam in the cylinder A in front of the piston can pass out through the ports c , c' , and e into the exhaust-pipe A^1 . When the piston B nears the end of its stroke, the friction-wheel D' on the cross-head D comes in contact with the curved end R^5 of the lever R and causes the latter to swing in the direction of the arrow i' , whereby the rod Q^3 is moved in the reverse direction of the arrow g' and the position of the slide-valves Q and Q' is reversed, so that the ports c , c' , and e are disconnected and the ports d , d' , and f are connected with each other. When the piston now travels in the reverse direction of the arrow g' , the exhaust takes place through the ports d , d' , and f in the same manner as above described in reference to the ports c , c' , and e . When the piston B travels in the reverse direction of the arrow g' and nears the end of its stroke, the friction-wheel D' comes in contact with the curved end R^6 of the lever R and causes the latter to swing in the reverse direction of the arrow i' , whereby the position of the slide-valves Q and Q' is again reversed to the position shown in Fig. 4. When the engine runs at a normal rate of speed, the frame L , carrying the friction-wheels L' and L^2 , stands at about the middle of the cam G^2 , so that the part of the cam G^2 coming in contact with the said friction-wheels L' and L^2 , as above described, opens and closes the slide-valves H and H' regularly. When the speed of the engine increases, the governor-weights P^3 slide outward and pull the collar O' upward by the ropes P , so that the bell-crank lever N is set in motion and moves the link L^4 , the rod L^3 , and the frame L transversely in the direction of the arrow k' , whereby the cam G^2 acts on the fric-

tion-wheels L' and L^2 , and thereby the valves H and H' are closed sooner, and consequently less steam is admitted to the cylinder A . The speed of the engine is thus decreased, and 5 when the normal speed is attained the governor-weights P^3 assume their former position by the action of the springs P^6 , whereby the collar O' is again moved downward to its former position by the action of the weights P^3 on the 10 bell-crank lever N , and the latter, the link L^4 , the rod L^3 , and the frame L also assume their former positions, and the valves H and H' are again opened and closed regularly. When 15 the speed of the engine decreases, the springs P^6 draw the weights P^3 still farther inward, so that the bell-crank lever N shifts the frame L transversely in a direction opposite to that described, whereby the cam G^2 holds the slide-valves H and H' open a longer time, so as to 20 admit more steam to the cylinder A . An increase of speed is thus obtained until the normal speed is reached and the weights P^3 of the governor O again assume their original 25 positions, whereby the frame L is moved to the middle of the cam G^2 , and the valves H and H' again open and close regularly.

It will be seen that as the cam G^2 is uniform in cross-section at points 2, 3, and 4 the valves H and H' always travel their full stroke, but 30 close sooner or later, according to the position of the frame L on the spiral cross-section of the cam G^2 . As the piston B always travels into full stroke, the exhaust slide-valves Q and Q' are opened and closed regularly, as 35 above described, by the action of the friction-wheel D' on the lever R , connected with the stem Q^3 of the said valves.

Having thus described my invention, what I claim as new, and desire to secure by Letters 40 Patent, is—

1. The combination, with the rotary cam, of a longitudinally-sliding valve-operating frame and a transversely-sliding frame thereon embracing a cam, substantially as set forth. 45 2. The combination, with a shaft having a fixed cam provided with a spiral ridge, of a longitudinally-sliding valve-operating frame under the cam at right angles to the shaft, and provided with a curved frame extending 50 over the cam and having front and rear friction-wheels for the cam to engage, substantially as set forth. 55 3. In a valve-gear, the combination, with a spiral cam secured to the main driving-shaft, of a frame mounted to slide transversely and carrying friction-wheels acted on by the said spiral cam, a second frame carrying the said first-named frame and connected with the steam-inlet valves, and a governor operated 60 from the main driving-shaft and controlling the transverse motion of the said first-named frame, substantially as shown and described.

4. In a valve-gear, the combination, with a main driving-shaft and a spiral cam secured 65 to the said main driving-shaft, of a frame mounted to slide transversely and carrying a friction-rollers acted on by the said cam, a

second frame, mounted to slide longitudinally, carrying the said first-named frame and connected with the steam-inlet valves, and a governor operated from the said main driving-shaft and controlling the transverse movement of the said first-named frame, substantially as shown and described. 70

5. In a valve-gear, the combination, with steam-inlet valves and a lever for controlling the said inlet-valves, of a frame held to slide and connected with the said lever, a second frame held to slide transversely on the said first-named frame, and a governor for controlling the transverse movement of the said second frame, substantially as shown and described. 75

6. The combination, with the crank-shaft, the cylinder, its piston, steam-chests, inlet slide-valves having stems extending toward each other, and exhaust-valves connected by a rod, of the cross-head connected to the piston-rod of said cylinder and operated by said crank, a cam on the crank-shaft, a lever extending between the two stems of said inlet-valves and oscillated by said cam, a rocking lever actuated by said cross-head, a rod connected to said lever and to the rod connecting the exhaust-valves, and a governor for changing the relation of the inlet-valve-operating frame with respect to the cam, substantially as set forth. 85 90

7. In a valve-gear, the combination, with a main driving-shaft, of a spiral cam secured on the said main driving-shaft, friction-wheels acted on by the said spiral cam, a frame mounted to slide transversely and carrying the said friction-wheels, a second frame carrying the said first-named frame and mounted to slide longitudinally, being also connected with the steam-inlet valves, a rod secured to the transversely-sliding frame, a link pivotally connected with the said rod, and a bell-crank lever pivotally connected by one arm with the said link, its other arm being acted on by the governor, substantially as shown and described. 100 105 110

8. In a valve-gear, a main driving-shaft, a governor operated from the said main driving-shaft, and a spiral cam secured on the said main driving-shaft, in combination with friction-wheels operated on by the said cam, a frame mounted to slide transversely and carrying the said friction-wheels, a second frame mounted to slide longitudinally and carrying the said first-named frame, being also connected with the steam-inlet valves, a rod secured on the said transversely-sliding frame, a link pivotally connected with the said rod, and a bell-crank lever pivotally connected by one arm to the said link, its other arm being acted on by the said governor, substantially as shown and described. 115 120 125
